(57) **CLAIM**

I claim the ornamental design of a valet organizer, as shown and described.

DESCRIPTION

FIG. 1 is an upper perspective view of a valet organizer. FIG. 2 is a front elevation view of the valet organizer of FIG. 1.

FIG. 3 is a rear elevation view of the valet organizer of FIG. 1.

FIG. 4 is a first side elevation view of the valet organizer of FIG. 1.

FIG. 5 is a second side elevation view of the valet organizer of FIG. 1.

FIG. 6 is a top plan view of the valet organizer of FIG. 1; and,

FIG. 7 is a bottom plan view of the valet organizer of FIG. 1.

The broken lines depict portions of the article that form no part of the claimed design.

1 Claim, 7 Drawing Sheets
